UNITED STATES PATENT OFFICE.

ARTHUR BREITFELD, OF ERFURT, GERMANY.

PEN.

SPECIFICATION forming part of Letters Patent No. 692,606, dated February 4, 1902.

Application filed July 12, 1901. Serial No. 68,064. (No model.)

To all whom it may concern:

Be it known that I, ARTHUR BREITFELD, apothecary, a subject of the King of Prussia, German Emperor, residing at Erfurt, in the 5 Kingdom of Prussia, German Empire, have invented certain new and useful Improvements in Pens, of which the following is a specification.

My invention relates to an improvement in pens; and it has for its object to so modify the construction of the pen that it can be used by those suffering from writer's cramp, and it is also particularly suited for writing an up-right hand. This is effected by shaping the 10 pen so that in writing it is moved by the writer rather with a pressure from the left to the right than with a pressure from the top to the bottom. This property is given to the pen by either grinding down the left side of the point 15 so that it slants to the right when looking at it from above—that is to say, making it unsymmetrical—or else, while the point is left even, it is split obliquely. In either case the left side of the pen when looking at it from 20 above will appear shorter than the right side thereof. If when writing the pen is held so as to rest on the left side of the point, the right-hand point of the pen will touch the paper above the left-hand point of the pen, and 25 in the act of writing the pen will glide over the paper with great ease. Both forms of the invention are illustrated by the annexed drawings, wherein—

Figure 1 shows a pen with obliquely-ground 30 point as seen from above. Fig. 2 shows the point of the pen according to Fig. 1 on an enlarged scale. Fig. 3 shows a pen split obliquely as seen from above. Fig. 4 shows the point of the pen according to Fig. 3 on an enlarged scale.

In the form illustrated by Figs. 1 and 2 the end of the point *a* of the pen has a straight split *b*, while the left-hand part of the point *c* is ground off obliquely at *d*, so as to recede as 40 compared with the right-hand part of the point *e*, and the right-hand point *e* will thus be made to come into contact with the paper above the left-hand point *c*. In the form of execution

according to Figs. 3 and 4 the split *b* of the point *a* is not situated in the straight line, (indicated by a dotted line,) but placed obliquely, and in this way the left point *c* is also made to recede as compared with the right-hand point *e*. If these pens are turned so as to rest on the left side of the point and one commences 50 to write, the pen will slide with great ease even over rough paper. There is no need to extend the fingers, and therefore even those affected with writer's cramp may easily write with this pen. In the same way this pen is 55 specially suited for writing an upright hand. The pen may also be used like any other steel pen hitherto in use by placing both parts *c* and *e* of the point on the paper side by side of each other.

Having now particularly described and ascertained the nature of my said invention and in what manner the same is to be performed, I declare that what I claim is—

1. As a new article of manufacture, a pen, 70 the left point of which recedes as compared with the right point and is shorter and narrower than the latter so that the right point will come into contact with the paper above the left point, the two points of the pen being 75 constructed so that a writing-point is presented free from angles and corners, substantially as set forth.

2. As a new article of manufacture, a pen 80 of the character which is always narrowing toward the writing end, having the left point thereof shorter and narrower than the right point so that the right point will come into contact with the paper above the left point, the two points of the pen being constructed so 85 that an easy-writing point is presented free from angles and corners, substantially as described.

In testimony whereof I have hereunto set my hand in presence of two subscribing witnesses.

ARTHUR BREITFELD.
